UNITED STATES PATENT OFFICE.

EMILE F. ESPERANDIEU, OF BUFFALO, NEW YORK, ASSIGNOR TO THE INTERNATIONAL INCINERATOR COMPANY, OF BUFFALO, NEW YORK.

INCINERATOR FOR GARBAGE, EXCREMENT, &c.

No. 893,229.

Specification of Letters Patent.

Patented July 14, 1908.

Application filed July 24, 1907. Serial No. 385,241.

To all whom it may concern:

Be it known that I, EMILE F. ESPERANDIEU, a citizen of the United States, residing at Buffalo, in the county of Erie and State 5 of New York, have invented certain new and useful Improvements in Incinerators for Garbage, Excrement, &c.; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of 15 this specification.

My invention relates to improvements in incinerators, its object being to provide means, preferably of a portable character, for the disposal of garbage and excrement by cremation, with wood, coal, or oil for fuel 20 and adapted for use at hospitals, private and boarding houses, hotels, schools, factories, camps, or other places which have no sewer connections, the idea being to effect the disposal of the garbage or excrement at the 25 points of accumulation, in a quick and efficacious manner and without the presence of offensive and dangerous odors.

To this end my invention consists of certain 30 details of construction; all of which will be fully hereinafter described and claimed.

In the drawings, Figure 1 is a side elevation of my improved incinerator. Fig. 2 is a central vertical section of Fig. 1, taken in 35 the line $x-x$. Fig. 3 is a top plan view, with portions broken away to show interior construction. Fig. 4 is a top plan view of the jointed two-part valve. Fig. 5 is a section taken in the line $z-z$ of Fig. 4.

Referring to the drawings, 1 is the metallic 40 casing, within which are arranged the operative parts. It rests upon the legs 2 and is provided in its top with an opening or seat 3, closed by the cover 4.

5 is the fire-box with door 6 and 7 is the ash-pit with door 8.

9 is the metallic pot or receptacle, suspended above the fire-box 5 upon trunnions, 50 its bottom resting in the opening 10 of the removable frame 11.

12 is a vertical draft-passage, connecting the upper space 13, between the pot 9 and the top of the casing, with the ash-pit 7. A passage 14 connects the upper space 13 in 55 the casing 1, with the smoke-pipe 15. This

passage 14 has an opening 16 in its top wall, in which is arranged a valve consisting of the two parts 17 and 18, the part 17 being hinged to the top wall of the passage and the part 18 being centrally hinged to the part 17, as clearly shown in Figs. 2 and 5.

In operation, to burn the accumulation in the pot 9, the two-part valve 17, 18, is left partially open, as shown in Fig. 2, to admit a current of air through opening 16, which 60 passes across the upper space 13, down the draft-passage 12, into the ash-pit 7, then up through the grate-bars 19, into the fire-box 5 and passing through the opening 10, in the removable plate 11, being confined to that 65 portion of the opening, which the lower portion of the receptacle 9 does not close or cover, and through the annular space above removable frame 11, it is carried through the communicating smoke-pipe 15. In this 70 manner all odors and products of combustion from the pot 9, are thoroughly consumed and carried off through the smoke-pipe 15. When my incinerator is in use as a closet, the two-part valve 17, 18, is closed 75 across the opening 16, as shown in Fig. 5 and all odors are then carried direct to the smoke-pipe, through the passage 14. The two-part valve 17, 18 may entirely close the passage 14 to the stack, yet at the same time may be 80 manipulated so as to govern the air fed in through the opening 16, or the opening 16 may be closed, in which case indirect communication with the smoke-stack is established. Thus graduated communication with 85 the atmosphere may be established, or indirect communication with the stack, but both cannot exist at the same time. The seat is 90 reached by the steps 20.

I claim.

A garbage or excrement incinerator comprising a portable metallic casing; a grate dividing the casing into a fire-box in its upper portion, and an ash-pit in its lower portion; a metallic receptacle situated in the upper portion of the fire-box and spaced from the top of the casing, said incinerator being formed with a passage, forming a communication between the space above said receptacle and the ash-pit; a smoke-pipe communicating directly with the fire-box; a passage communicating with the smoke-pipe and with the space above the receptacle for disposing of the back-draft, and provided with an opening for admitting air, a damper or valve in 110

said passage for simultaneously closing the
passage from the smoke-pipe and placing the
space above the receptacle in graduated
communication with the outside atmosphere
5 through the opening in the passage, all com-
bined and operating as and for the purpose
stated.

In testimony whereof, I have signed my
name to this specification, in the presence of
two subscribing witnesses.

EMILE F. ESPERANDIEU.
